United States Patent Office

Des. 197,252
Patented Dec. 31, 1963

197,252

JEWELRY BOX

Katherine T. Spears, 814 Raab St., Victoria, Tex.

Filed June 15, 1962, Ser. No. 70,561

Term of patent 14 years

(Cl. D58—12.7)

The essential features of my design reside in the portions shown in full lines.

I claim:

The ornamental design for a jewelry box, as shown and described.
